H. JONES.

APPARATUS FOR TIGHTENING AND FASTENING BANDS AROUND CASES AND THE LIKE.

APPLICATION FILED FEB. 21, 1916.

1,206,853.

Patented Dec. 5, 1916.

Inventor: *Hyman Jones*
By *Paul Boisjoly, Attorney.*

UNITED STATES PATENT OFFICE.

HYMAN JONES, OF MELBOURNE, VICTORIA, AUSTRALIA.

APPARATUS FOR TIGHTENING AND FASTENING BANDS AROUND CASES AND THE LIKE.

1,206,853.

Specification of Letters Patent.

Patented Dec. 5, 1916.

Application filed February 21, 1916. Serial No. 79,714.

To all whom it may concern:

Be it known that I, HYMAN JONES, a subject of the King of Great Britain and Ireland, and a resident of the postal district of Carlton, a suburb of the city of Melbourne, in the county of Bourke, State of Victoria, Commonwealth of Australia, whose post-office address is 52-56 Bouverie street, in the said postal district of Carlton, have invented a certain new and useful Improved Apparatus for Tightening and Fastening Bands Around Cases and the like, of which the following is a specification.

This invention relates to boxes or cases protected by external hoop iron or like bands. Each band when being applied requires its ends drawn toward each other to be riveted together. Such bands have been strained or the two ends drawn together and then united or secured in a variety of ways. Objections existed to some of the appliances hitherto used as they were heavy and cumbrous, were comparatively slow in operation, and an apparatus was not quickly transferable to the next band to be tightened. In addition to the foregoing complete control was not easily retained of the operating parts while the two band ends were being drawn together or tightened and a punching apparatus used for forming a hole through each band end could not always be conveniently controlled while the punch was being forced through the ends of the bands to receive a rivet.

The object of this invention is to provide apparatus whereby the two ends of a band are drawn together with ease and despatch and then with equal facility locked together by riveting. Not only are the parts light but they are also strong, special provision being made whereby a tightening screw can be actuated at two speeds, a slow speed for tightening the bands and a fast one for withdrawing cams and their accessories.

The control of the apparatus while the tightening screw is being actuated is also effected by a control handle. Another control handle effects the same purpose on a punching apparatus, the punch of which is retained in its holder in such a manner that it turns with the holder and not independently of the same. The features of novelty are pointed out in the appended claims.

Referring to the drawings which form a part of this specification, Figure 1 is a perspective view of a straining, punching and

riveting apparatus complete and in position on a box. For convenience of illustration a far cam lever is down and its band end free. A punch block is in place 60 and one of the meeting ends of the bands is overlapping the other and ready to be punched. Fig. 2 is a side view of a slide block having an extension thereon and a control handle. Fig. 3 is a sectional view showing a toothed sleeve around the plain part of a tightening screw. Fig. 4 is a part sectional view of a punch holder and locking screw. Fig. 5 is a view of the punch block showing a rivet being inserted in a band. 70 Fig. 6 is an enlarged sectional view of a sliding block extension having a handle retaining bridge. Fig. 7 is a perspective view on a reduced scale of a removable handle for use with a sliding block having an extension as seen in Fig. 6. Fig. 8 is a reduced sectional view of the base plate of a punch block having a handle retaining bridge, the handle seen in Fig. 7 being used 75 with both the sliding block and the punch block when they are provided with bridges. 80

This invention includes a base plate 2 at each end of which is riveted, bolted, or otherwise secured a bearing 3. Inside the said bearings is situated a right and left handed tightening screw having a right hand thread 4 and a left hand thread 5. Between these two is a central plain part 6. On one end of the screw is secured a hand wheel 7. Around the central plain part 6 is a sleeve 8 locked to the said plain part by a locking pin 9. Protruding from the sleeve are teeth 10. Around the sleeve is a split yoke having a right leg 11 and a left leg 12. Between the two legs is a pivot pin 13 upon which is pivoted a pawl 14. The upper end of the split yoke is provided with a divided socket pin 15 upon which drops a removable socket handle 16. 90

In combination with the foregoing are 100 slide blocks 17, on each side of which is a guide lip 18. Through each slide block is a threaded hole passing one of the tightening screw threads. Protruding from one of the blocks is an extension 19 to which is 105 attached the lower end of an upraised control handle 20. Outstanding from each block is a foot 21 and above it outstands a cam pin 22 upon which turns a cam 23 operated by a cam lever 24.

The above apparatus is used for drawing the two band ends together. For riveting

the two band ends a punch block is provided having a base plate 25. Through this is a punch hole to pass the punchings made by the punch. Formed in the surface of the 5 base plate are two hollows 26 between which is an elevated ridge 27. Through the said base plate pass rivets or other attachments to secure the inner end of the upraised punch block holding handle 28. Above the punch 10 block stands a head 29 beneath which is a gullet or mouth to pass the bands to be punched and riveted. Through the said head is a vertical threaded hole.

Into the threaded hole before referred to 15 is placed the screw threaded portion 30 of an upraised punch holding handle 31. Within the threaded portion of this handle is a hole to accommodate the upper end of a punch. Through the wall of the inner end 20 of the said handle is a threaded hole to accommodate a locking screw 32.

In the hole in the threaded portion of the punch holding handle before referred to is situated a socket pin 35 in which is a locking screw hole 36. The punch has a punch 25 portion 33 and a collar 34.

Instead of a control handle being secured to the extension 19 of one of the sliding blocks 17 the said extension may be provided with an upraised handle retaining bridge 37 forming a socket indicated at 38. Instead, also, of a punch block holding handle being secured to the base plate 25 the 30 said plate may be provided with an upraised handle retaining bridge 39 forming a socket indicated at 40. When the bridges 37 and 39 are provided a single removable control handle 41 is employed having a foot 42. As the sliding and punch block are not in 40 use simultaneously it is obvious that the foot 42 may be inserted in the socket of the element being operated to steady it.

This invention is operated as follows:— The base plate 2 is placed upon the top of 45 the box and by the hand wheel 7 the slide blocks 17 are moved to their outward extremities. The cam levers 24 are then lowered and the band ends 43 and 44 respectively are placed between a cam and a 50 foot 21. The cam levers 24 are then elevated and the band ends thereby locked to the slide blocks. The removable socket handle 16 is then placed over the divided socket pin 15 and the ratchet pawl 14 moved backward 55 and forward thereby drawing the two slide blocks together. The band ends are thereby also drawn together until they overlap each other. The apparatus is steadied by the handle 20. When sufficiently tight the base 60 plate 25 is passed underneath the two ends and the punch holding handle 28 rotated. A hole is thereby formed through the two meeting ends 43 and 44. The punch block is steadied by the handle 28. When the hole 65 is punched the punch base is moved side-

wardly until the elevated ridge 27 is situated directly beneath the punch holes. A bifurcated rivet, legs downwardly, is then driven through the hole in the two band ends and the legs as they press against the 70 ridge 27 are separated one from the other and the said ends turn back upon the inside of the inside band. The band ends are thereby locked together. A second hole is then punched and another rivet inserted. 75 The cam levers are then depressed releasing the band ends and by the hand wheel 7 the slide blocks are moved from each other in order that the ends of a fresh band may be treated as before described. 80

Having now described my invention, what I claim as new and desire to secure by Letters Patent is:—

1. Improved apparatus for tightening and fastening bands around cases and the like, 85 consisting in the combination of a base plate, a tightening screw mounted above said plate, said screw having a right hand thread and a left hand thread between which is a plain part, a toothed sleeve secured to said plain 90 part, a split yoke having a pawl engaging the teeth of the sleeve, a removable socket handle engaging the yoke, a slide block for each thread of the tightening screw, an extension protruding from one of the blocks, 95 an upraised control handle secured to the extension, a foot outstanding from each block and a cam disposed above each foot.

2. Improved apparatus for tightening and fastening bands around cases and the like, 100 consisting in the combination of a base plate, a tightening screw mounted above said plate, a hand wheel secured to one end of the screw, said screw having a right hand thread and a left hand thread between which is a plain part, a toothed sleeve secured to said plain part, a split yoke having a pawl engaging the teeth of the sleeve, a removable socket handle engaging the yoke, 105 a slide block for each thread of the tightening screw, an extension protruding from one of the blocks, an upraised bridge carried by the slide block extension, said bridge forming a socket, a control handle having a foot for insertion in the socket, a foot outstanding from each slide block and a cam disposed above each foot.

3. Improved apparatus for tightening and fastening bands around cases and the like, 110 consisting in the combination of a base plate, a bearing at each end thereof, a tightening screw mounted in the bearings, said screw having a right hand thread and a left hand 115 thread and a central plain part between said threads, a hand wheel secured to one end of the screw, a sleeve mounted on the plain part, a locking pin holding said sleeve to said plain part, teeth protruding from said sleeve, a split yoke having a right leg and a left leg embracing the sleeve, a piv- 120

125
130

- oted pawl disposed between the legs and engaging the teeth of the sleeve, said yoke having a socket pin at its upper end, a removable socket handle engaging the socket 5 pin, a slide block for each thread of the tightening screw, a guide lip at each side of each block engaging the base plate, an extension protruding from one of the slide blocks, an upraised bridge carried by the 10 extension, said bridge forming a socket, a handle having a foot passing into the socket, a foot outstanding from each slide block, a cam pin above the outstanding foot, a cam mounted upon the cam pin, and a lever for 15 operating the cam.
4. In a band-tightener, the combination, with a rotatable tightening screw having a right-hand thread, a left-hand thread and an intermediate plain portion; of a pair 20 of sliding clamps, one for each end of the band, mounted on said screw for movement toward each other when the screw is rotated; and an operating device for said screw, comprising a split yoke lever loosely 25 mounted on the screw and having a split pin protruding from its upper end, a member fixed to the plain portion of said screw and disposed between the legs of the lever, an actuating member carried by said lever 30 to engage and rotate said fixed member, and a socket handle removably fitted on said pin.
5. In a band-tightener, the combination, with a rotatable tightening screw having 35 a right-hand thread, a left-hand thread and an intermediate plain portion; of a pair of sliding clamps, one for each end of the band, mounted on said screw for movement toward each other when the 40 screw is rotated; and an operating device for said screw, comprising a split yoke lever loosely mounted on the screw, a member fixed to the plain portion of said
- screw and disposed between the legs of the lever, and an actuating member carried by 45 said lever to engage and rotate said fixed member.
6. In a band-tightener, the combination, with a rotatable tightening screw, and means actuated thereby for drawing the ends of 50 the band together; of a device for rotating said screw comprising a split yoke lever loosely mounted on the screw and having a split pin protruding from its upper end, a member fixed to said screw between the 55 legs of the lever, an actuating member carried by said lever to engage and rotate said fixed member, and a socket handle removably fitted on said pin.
7. In a band-tightener, the combination, 60 with a pair of slide blocks, to which the ends of the band are adapted to be connected, and means for effecting relative movement between said blocks in a direction to draw said band ends together; of an extension 65 projecting from the bottom of one block; and a handle for controlling said block during the operation of said block-moving means, attached at its lower end to said extension and projecting upwardly and outwardly away from said extension.
8. In a band-tightener, the combination, 70 with a pair of slide blocks, to which the ends of the band are adapted to be connected and means for effecting relative movement between said blocks in a direction to draw said band ends together; of an extension 75 projecting from the bottom of one block and formed with a bridge providing a socket; and a handle for controlling said block during the operation of said block-moving means, provided with a foot inserted in said socket.

In testimony whereof I affix my signature.

HYMAN JONES.
